US00D896872S

(12) **United States Design Patent** (10) **Patent No.:** **US D896,872 S**
(45) **Date of Patent:** **** Sep. 22, 2020**

(54) **INTERCHANGEABLE LENS FOR CAMERA**

(71) Applicant: **SAMYANG OPTICS CO., LTD.**,
Gyeongsangnam-do (KR)

(72) Inventor: **Han Jea Lee**, Gyeongsangnam-do (KR)

(73) Assignee: **SAMYANG OPTICS CO., LTD.**,
Changwon-si (KR)

(**) Term: **15 Years**

(21) Appl. No.: **29/643,319**

(22) Filed: **Apr. 6, 2018**

(30) **Foreign Application Priority Data**

Jan. 22, 2018 (KR) 30-2018-0003565

(51) **LOC (12) Cl.** **16-05**

LLP; Jonathan Pearce

(57) **CLAIM**

The ornamental design for the interchangeable lens for camera, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office file or records, but reserves all other copyright rights whatsoever. FIG. 1 is a perspective view of the interchangeable lens for camera

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings illustrate portions of the interchangeable lens for camera and form no part of the claimed design.

1 Claim, 7 Drawing Sheets
